UNITED STATES PATENT OFFICE.

JOHN C. BERGER, OF MICHIGAN CITY, INDIANA.

REFRIGERATOR.

SPECIFICATION forming part of Letters Patent No. 396,261, dated January 15, 1889.

Application filed May 17, 1888. Serial No. 274,153. (No model.)

To all whom it may concern:

Be it known that I, JOHN C. BERGER, a citizen of the United States of America, residing at Michigan City, in the county of La Porte and State of Indiana, have invented certain new and useful Improvements in Refrigerators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain new and useful improvements in refrigerators; and it consists in the special construction and combination of the parts, as will be hereinafter fully set forth, and specifically pointed out in the claims.

In the accompanying drawings, Figure 1 is a perspective view of my improved refrigerator, and Fig. 2 a vertical sectional view.

The exterior of the refrigerator is practically of ordinary construction, being provided in front with doors, so that access can be had to the provision-chamber, and on top with a hinged lid to permit ice to be placed in the ice-chamber. To the under side of this lid is secured a corrugated metal plate, A, having longitudinal depending flanges *a*, the flange adjacent to the hinges being adapted to abut against the upper edge of the back wall of the ice-chamber, while the front flange 35 fits against the upper edge of the interior front wall. To the inner side walls, near the top, are secured triangular strips B, and at the corners of the refrigerator are secured vertical strips B', which extend from the triangular strips B downwardly to the bottom of the ice-chamber.

At the upper portion of the provision-chamber are rigidly secured to the front and rear sides of the refrigerator cross-pieces or boards C C and C', the edges of which are separated from each other to provide air-passage ways *d d* at the sides of the refrigerator and central air-passages, *e e*. The central board, C', is slightly hollowed from front to rear.

50 Above the boards C, hereinbefore referred to, is secured an open-topped box or casing, E', forming the ice-chamber, which is prefer-

ably made of metal, the bottom *e*² thereof, at its rear, having an opening, to which a drip-pipe, E, is connected, said drip-pipe passing down through the provision-chamber and out at the bottom of the refrigerator. The bottom *e*² of the ice-chamber E', hereinbefore described, is provided with slots or openings *e'*, having slight upwardly-projecting walls *d'*. 60 These upwardly-projecting flanges prevent the water from the melting ice dropping into the provision-chamber.

The lower chamber of the refrigerator is metal lined in the usual manner, and the 65 walls are also provided with a packing of non-conducting material, as shown.

F refers to an ice-tray, made of corrugated metal and provided with upwardly-projecting sides F', the corrugated bottom *f'* thereof 70 having slots *f*. To the longitudinal edges of the bottom *f'* of the tray are secured strips *g*, which rest upon the bottom *e*² of the ice-chamber and provide a space between the bottom *f'* of said tray and the bottom of the 75 ice-chamber.

The construction hereinbefore described provides means whereby the cold air from the ice can descend through the openings *f* in the corrugated bottom, upon which the ice 80 rests, and through the openings *e'* in the bottom of the ice-chamber into the provision-chamber, while the warmer air from the provision-chamber can rise through the openings *d* through the side flues, *d*², with which 85 said openings connect, and over the sides F' into the ice-chamber, so as to keep up a continuous circulation of air in the refrigerator.

Beneath the openings *e*, through which the cold air descends, are pans H H, which are 90 maintained in position by having one edge thereof placed in a recess formed in strips *h*, secured to the under side of the boards C. The rear sides of these pans are flanged outwardly and held in place by pivoted plates *i*. 95 The inner edges of these pans are bent slightly upward, so as to provide shallow receptacles which will hold any moisture which may condense therein.

Beneath the central board, C', and above the 100 drip-pans H are secured brackets, which support glass plates J J, designed to condense moisture in the air circulating in the refrigerator.

The pans hereinbefore referred to may have suitable openings or stoppers for withdrawing the water which may collect therein.

I claim—

- 5 1. In a refrigerator, the combination, substantially as described, of the ice-chamber having an inclined bottom provided with flanged openings, fixed supports for the bottom of the ice-chamber, an ice-tray of corrugated metal provided with upwardly-projecting ends, and strips secured vertically in the corners of the ice-chamber to support the upwardly-projecting ends of the tray against outward pressure.
- 5 2. In a refrigerator, the combination, substantially as described, of the metal-lined ice-chamber occupying the entire upper part of the refrigerator and having its bottom provided with flanged openings, a removable

metal ice-tray having openings in its bottom 20 and upwardly-projecting ends extending to near the top of the ice-chamber, strips arranged vertically in the corners of said chamber to support the upwardly-projecting ends of the tray at a little distance from the ends 25 thereof, and triangular strips connecting the upper ends of the vertical strips and serving to deflect any air-currents that may rise through the spaces between the ends of the ice-chamber and the upwardly-projecting 30 ends of the ice-tray.

In testimony whereof I affix my signature in presence of two witnesses.

JOHN C. BERGER.
